UNITED STATES PATENT OFFICE

106,875

DESIGN FOR A MACHINE TOOL BASE

Harold Van Doren, Toledo, Ohio, assignor to
Ex-Cell-O Corporation, a corporation of Michigan

Application April 14, 1937, Serial No. 68,752

Term of patent 14 years

To all whom it may concern:

Be it known that I, Harold Van Doren, a citizen of United States, residing at 1217 Madison Avenue, Toledo, in the county of Lucas and State of Ohio, have invented a new, original, and ornamental Design for a Machine Tool Base, of which the following is a specification, reference being had to the accompanying drawing, forming part thereof.

Figure 1 is a front perspective view of a machine tool base showing my new design, and

Fig. 2 is a rear perspective view thereof.

The dominant feature of the design is the base having three grooves around the upper extended portion thereof and three relatively wider and more widely spaced grooves around the lower portion thereof.

I claim:

The ornamental design for a machine tool base substantially as shown and described.

HAROLD VAN DOREN.
